J. L. A. BIZIER

BOX HOLDING DEVICE

Filed May 14, 1924

Inventor
Joseph Louis Arthur Bigler

by Jas. H. Churchill.

Attorney

UNITED STATES PATENT OFFICE.

JOSEPH L. A. BIZIER, OF MEDFORD, MASSACHUSETTS.

BOX-HOLDING DEVICE.

Application filed May 14, 1924. Serial No. 713,340.

To all whom it may concern:

Be it known that I, JOSEPH LOUIS ARTHUR BIZIER, a citizen of the United States, residing in Medford, in the county of Middlesex and State of Massachusetts, have invented an Improvement in Box-Holding Devices, of which the following description, in connection with the accompanying drawing, is a specification, like characters on the drawing representing like parts.

This invention relates to a box-holding device particularly adapted to be employed for holding the usual form of metal box containing paste used for polishing shoes.

The invention has for an object to provide a novel and highly efficient box-holding device, which has provision for securely holding the box therein, and for permitting the box to be conveniently removed therefrom. A further object of the invention is to provide a box-holding device of a simple and practical construction, which may be economically manufactured, and by which the operator may conveniently hold the box when using the contents thereof.

To these ends the improved box-holding device is provided with a plurality of members for engaging the sides of the box and one of which is movably secured in its box-engaging position to be capable of being moved into an open position when it is desired to remove the box from the holder or to insert the box into the holder. The improved box-holding device is preferably provided with a handle for permitting the operator to hold the device and box without liability of soiling the hands, and mechanism is also preferably provided for mechanically opening the cover of the box held by the holding device.

These and other features of the invention will be hereinafter described and particularly defined in the claims at the end of this specification.

In the drawing illustrating the preferred embodiment of the invention, Fig. 1 is a plan of the improved box-holding device, Fig. 2 is a vertical section on line 2—2 of Fig. 1, Fig. 3 is a side elevation of the device illustrating the mechanism for opening the cover of the box, Fig. 4 is a plan view of the box-holding portion of the device illustrating the manner in which the box may be removed from or inserted into the device, and Figs. 5 and 6 are details in

section on lines 5—5 and 6—6 of Fig. 1 respectively.

Referring to the drawing the box-holding device illustrated therein is particularly designed for holding a metal box containing paste used in polishing shoes and which has a general shape illustrated in Figs. 1, 2, 3, and 4, and is provided with a removable cover 10 having a flange 12 near its lower edge. The cover 10 is adapted to fit over the lip 13 of the body portion of the box above the usual flange 14 thereon. In general the improved box-holding device comprises a supporting member 15 upon which the bottom of the box rests and which is provided with two sets of box holding members 16, 17, adapted to engage the sides of the box, to clamp the same securely in position upon the supporting member 15. One box-holding member 17 is movably connected with the supporting member 15 to be capable of movement from its closed or box-holding position into its open position in which latter it permits the box to be removed from and to be inserted into the box-holding device. The supporting member 15 is also provided with a handle 18 integral therewith, and in practice the supporting member 15, handle 18, and the stationary box-engaging members 16 are preferably formed of sheet metal stamped from a single piece thereof. As herein shown, the stationary box-engaging member 16 comprises two arms spaced apart and upstanding from the supporting member 15 and the upper ends of which are bent inwardly to form hooks 20 adapted to extend over the flange 14 upon the body portion of the box. The movable box-holding member 17 preferably comprises a sheet metal arm pivotally secured to the supporting member 15 to be capable of movement from the box-holding position illustrated in Fig. 1 to that illustrated in Fig. 4. The upper end of the arm 17 is bent inwardly to form a hook 22 adapted to extend over the flange 14 of the box. Provision is made for drawing the arm 17 inwardly when it is moved from its open position shown in Fig. 4 into its closed position shown in Fig. 1, in order to clamp the box 10 between the arm 17 and the two stationary members 16. For this purpose the arm 17 is provided with a slot 24 through which the pivot 25 extends, and the inner end of the arm 17 is provided

with a finger 27 bent upwardly and extended through a curved slot 28 in the supporting member 15. The slot 28 is eccentrically arranged with respect to the pivot 25 of the arm 17, so that when the arm 17 is rotatively moved from its open position shown in Fig. 4 into its closed position shown in Fig. 1, the inner wall 29 of the slot 28 co-operates with the upwardly extended finger 27 to form in effect a cam, which operates to bodily move the arm 17 inwardly and draw it into its closed position and force the box against the members 16. The slot 24 through which the pivot 25 extends permits this inward bodily movement of the arm. Provision is made for removably locking the movable arm 17 in its closed position, and for this purpose as herein shown, the supporting member 15 is slit to provide a yielding stop or latch 31, which in its raised position normally prevents pivotal movement of the arm 17 from its closed position illustrated in Fig. 1. The operator depresses the yielding latch 31 when it is desired to swing the arm into its open or closed position.

In order to mechanically open the cover of the box held by the improved holding device, the latter is provided with an arm 32 having a finger 33 adapted to be positioned between the flanges 12, 14 upon the cover and the body portion of the box respectively, when the box is inserted into the holder. The arm 32 is extended through an opening in the handle 18 and is connected at its lower end by a spring arm 34 to the outer end of the handle so as to permit the operator to push the spring arm 34 toward the handle from the position shown in Fig. 2 to that shown in Fig. 3, and thereby cause the arm 32 to bodily lift the cover from the box by the co-operation of the finger 33 with the flange 12 upon the cover of the box. The spring 34 flexes at such time, and when the cover has been removed, the said spring operates to again lower the finger into the position illustrated in Fig. 2.

In the illustrated box-holding device, the movable box-engaging member 17 in its closed position is separated from each of the stationary members 16 by arcs of substantially 120 degrees, and the cam slot 28 is arranged to permit movement of the movable box-engaging member 17 into its open position substantially in alignment with one of the arms of the stationary member 16 to provide an opening of a width at least equal to

the diameter of the box and through which the box may be slid outwardly to be removed from the holding device.

From the description thus far, it will be observed that by means of the present holding device, a box containing the usual paste employed for polishing shoes may be held in a convenient manner, eliminating the liability of soiling the hands. The improved box-holding device finds use in the commercial boot-blacking establishments and also by individuals.

While in its preferred form the invention is embodied in a device for holding a box containing polishing paste, it is not desired to limit the invention in this respect, as it may be embodied in other forms for holding other boxes within the scope of the following claims:

1. A box-holding device comprising a supporting member provided with a stationary box-engaging member and with a cam slot, and a box-engaging member pivotally secured to said supporting member and engaged with said cam slot to be bodily moved thereby toward and from the stationary box-engaging member when the movable box-engaging member is rotated in opposite directions.

2. A box-holding device comprising a supporting member provided with a stationary box-engaging member, and a movable box-engaging member, means for effecting bodily movement of the movable box-engaging member, said movable box-engaging member being pivotally secured to said supporting member and engaged with said means to be bodily moved thereby toward and from the stationary box-engaging member when the movable box-engaging member is rotated in opposite directions.

3. A box-holding device comprising a handle provided at one end thereof with box-holding members having provision for removably securing a box in an operative position upon the handle, and means carried by the handle for mechanically opening the cover of a box held by the box-holding members, comprising a finger for engaging the cover capable of being lifted by the operator and a spring connecting the finger with the handle for returning the finger to normal position after the cover has been opened.

In testimony whereof, I have signed my name to this specification.

JOSEPH L. A. BIZTER.
